UNITED STATES PATENT OFFICE.

CHARLES S. EPPLEY, OF YORK, PENNSYLVANIA, ASSIGNOR TO SELF-ACTING SWITCH CO., OF YORK, PENNSYLVANIA, A CORPORATION OF DELAWARE.

TROLLEY CONTACT.

Application filed October 11, 1926. Serial No. 140,881.

This invention relates to means for automatically closing the circuits of switch mechanism of railways, particularly street railways, whereby the switches may be automatically operated by electrically actuated mechanism included in a circuit, which is adapted to be closed by the trolley wheel either directly or indirectly according to the system employed.

10 The present invention appertains to the circuit closing means which is mounted upon the trolley wire and adapted to be operated by the trolley wheel for completing a circuit to actuate the mechanism for 15 operating the switch mechanism or other part to be moved.

While the drawings illustrate a preferred embodiment of the invention, it is to be understood that in adapting the means to 20 meet specific needs and requirements, the design may be varied and such other changes in the minor details of construction may be resorted to within the scope of the invention as claimed, without departing from 25 the spirit thereof.

For a full understanding of the invention and the merits thereof reference is to be had to the following description and the drawings hereto attached, in which:

30 Figure 1 is a side view of a trolley contact embodying the invention, the guide at one end being in section.

Figure 2 is a top plan view of the parts illustrated in Figure 1.

35 Figure 3 is a transverse sectional view on the line 3—3 of Figure 2.

Figure 4 is a similar sectional view on the line 4—4 of Figure 1, looking in the direction of the arrows.

40 Corresponding and like parts are referred to in the following description and designated in the several views of the drawings by like reference characters.

The numeral 1 designates the trolley wire 45 of an electrically operated railway system. The circuit closing means embodying the invention are mounted upon the trolley wire 1, and include a body of insulating material and, as shown, this body comprises similar 50 members 2 in the form of strips disposed upon opposite sides of the trolley wire and clamped thereto by means of bolts 3, each of the strips being partly grooved to form an opening when the strips are assembled 55 for the reception of the trolley wire. The

opposing faces of the strips 2 are cut away below the opening formed by the matching grooves to provide a space 4 for the circulation of air and the escape of any moisture that may find its way into the trolley wire 60 receiving opening of the body. The lower end portions of the strips 2 are beveled upon their outer sides to conform somewhat to the groove of the trolley wheel.

Similar metallic contact strips 5 are applied to the outer sides of the body strips 2 and are retained in place by means of the bolts 3 and other fastenings 6, the latter partaking of the nature of rivets. The lower edge portions of the contact strips 5⁷⁰ are deflected inwardly to conform to the beveled sides of the body strips 2. The lead wire from the electrically operated switch mechanism is designated by the numeral 7⁷⁵ and may be connected to a contact strip in any determinate way.

A contact plate 8 is disposed at one side of the body and is normally spaced from the adjacent contact strip 5 and is attached at its upper end to a strip 9 of insulating material which is supported above the body by means of uprights 10 which, as shown, consist of metal strips soldered or otherwise attached to the contact strip 5 adjacent the contact plate 8. The strip 9 of insulating material, being disposed against the outer side of the supporting strips 10, serves to space the contact plate 8 from the contact strip 5. The lower end of the contact plate 8 is deflected inwardly to conform to the lower beveled side of the main body. A conductor 11 is connected to the contact plate 8 in any determined way and leads from the part through which the circuit is to be closed.

95 A guide is located at each end of the body to insure the trolley wheel passing smoothly from the trolley wire onto the body and from the latter back upon the trolley wire. This guide consists of a block 12 of insulating material having a groove or channel in its top side for the reception of the trolley wire, a top plate 13 being secured to the top of the block and having a tongue to enter the groove or channel of the block 12 and clamp the trolley wire so as to hold the guide in place. A tapered extension 15 projects outwardly from the block 12 and is grooved in its top side to receive the trolley wire. The bottom and opposite sides of the extension 110

15 taper outwardly toward the sides of the trolley wire to present a practically unobstructed passage between the guide and trolley wire to admit of the trolley wheel 5 passing upon and leaving the guide without any appreciable jar.

It is observed that while one contact element 8 only is illustrated, any desired number may be provided, depending upon the 10 mechanisms included in circuits to be closed in the automatic operation of the switch mechanism or the like.

Having thus described the invention, what I claim is:

15 1. Circuit closing means for electrically operated switch mechanism for railways, the same comprising an elongated body of insulating material comprising longitudinal sections adapted to receive the trolley wire 20 therebetween, means for securing the sections and clamping them upon the trolley wire, contact strips along the outer sides of the body, a strip of insulating material supported above and at one side of the body, 25 and a contact element attached at its upper end to the said insulating strip and extending along the side of the said body and spaced from the adjacent contact strip.

2. Circuit closing means for electrically

operated switch mechanism for railways, the 30 same comprising an elongated body of insulating material adapted to be mounted upon a trolley wire, metallic contact strips at the sides of the said body, supporting elements extending upwardly from one of the metal 35 contact strips, an insulating strip connected to the upper ends of the supporting strips, and a contact plate attached at its upper end to the insulating strip and extending along the outer side of the metal contact strip and 40 spaced therefrom.

3. A trolley contact comprising companion strips of insulating material having matching grooves in adjacent sides to receive the trolley wire, means for connecting the said 45 strips and clamping the trolley wire therebetween, metal contact strips placed against the outer sides of the body strips, spaced supports projecting upwardly from one of the contact strips, an insulating strip connecting the upper ends of said spaced supports, and a 50 contact plate attached at its upper end to the said insulating strip and extending along the outer side of the body and spaced from the adjacent contact strip.

In testimony whereof I affix my signature.

CHARLES S. EPPLER. [I. S.]
